United States Patent Office

Des. 195,830
Patented Aug. 6, 1963

195,830

BUILDING

Pearl L. Schluttig, P.O. Box 7544, Washington, D.C.

Filed Nov. 5, 1962, Ser. No. 72,390

Term of patent 14 years

(Cl. D13—1)

FIG. 1.

FIG. 2.

FIG. 3.

FIG. 1 is a front elevational view of a building, showing my new design;

FIG. 2 is a rear elevational view thereof, and

FIG. 3 is a side elevational view thereof. The other side is substantially the same as the side shown.

I claim:

The ornamental design for a building, substantially as shown and described.
